UNITED STATES PATENT OFFICE

98,165

DESIGN FOR A SADIRON HANDLE

Ivar Jepson, Chicago, Ill., assignor to Chicago
Flexible Shaft Company, Chicago, Ill., a cor-
poration of Illinois

Application September 30, 1935, Serial No. 58,764

Term of patent 7 years

To all whom it may concern:

Be it known that I, Ivar Jepson, a citizen of the United States, residing at Chicago, in the county of Cook and State of Illinois, have invented a new, original, and ornamental Design for a Sadiron Handle, of which the following is a specification, reference being had to the accompanying drawing, forming part thereof.

In the drawing:

Figure 1 is a perspective of a handle showing my design;

Fig. 2 is a side view thereof, and

Fig. 3 is a top view thereof.

I claim:

The ornamental design for a sadiron handle substantially as shown.

IVAR JEPSON.
